UNITED STATES PATENT OFFICE.

FLOYD A. RUCKMAN, OF COLUMBIA CITY, INDIANA, ASSIGNOR TO JOHNSON ACETYLENE GAS COMPANY, OF CRAWFORDSVILLE, INDIANA, A CORPORATION.

ACETYLENE-GENERATOR.

1,813,607.

Specification of Letters Patent. Patented Aug. 19, 1919.

Application filed February 6, 1918, Serial No. 215,672. Renewed May 13, 1919. Serial No. 296,926.

To all whom it may concern:

Be it known that I, FLOYD A. RUCKMAN, a citizen of the United States, residing at Columbia City, in the county of Whitely and State of Indiana, have invented certain new and useful Improvements in Acetylene-Generators; and I do declare the following to be a full, clear, and exact description of the invention, such as will enable others skilled in the art to which it appertains to make and use the same.

My invention relates to acetylene generators and its object is to provide a generator which will automatically control the pressure of the gas generated therein in such a manner as to provide a uniform pressure with the minimum amount of actuation of the carbid feed valve and which will furthermore provide a means to prevent the generation of a dangerous pressure within the generator casing.

Another object of my invention is to provide a carbid feed valve in a generator of this character which is positive in action and which will provide a positive cut-off for the carbid when through any cause the valve is opened to such an extent as would ordinarily cause a dangerous pressure to be formed within the generator.

A further object of my invention is to provide in a generator of this character a carbid valve which is self-cleaning and which is so constructed as not to obstruct the free flow of carbid therethrough and which is positive in action.

With these and other general objects in view which will appear from the description my invention resides in the novel combination, construction and arrangement of parts to be more fully hereinafter described and claimed when taken in connection with the accompanying drawings which form a part of this application and in which:

Figure 1 is a vertical sectional view of a generator illustrating the application of my improved valve;

Fig. 2 is a side elevation on a slightly enlarged scale of my valve;

Fig. 3 is a longitudinal section thereof;

Fig. 4 is a detail vertical section through my valve showing it disposed at one stage in its operation;

Fig. 5 is a similar view illustrating the valve in the final stage of its operation;

Fig. 6 is a horizontal section on line 6—6 of Fig. 4; and,

Fig. 7 is a vertical sectional view substantially on the line 7—7 of Fig. 2.

Briefly described my invention comprises substantially an acetylene generator of the pit type provided with a pressure controlled gas bell or gasometer and having contained therein a novel form of carbid magazine which magazine is provided with a novel form of carbid feed valve to be more fully hereinafter described. The feed valve, commonly called shoe, is substantially a receptacle which is pivotally swung below the mouth of the carbid magazine and is so formed as to be spaced slightly below the mouth of the magazine to normally receive the carbid therein from the magazine. Operating means are provided whereby the valve is oscillated or tilted below the mouth of the carbid magazine whereby the carbid will be discharged through an aperture provided in one of the walls of the receptacle.

Heretofore in the construction of carbid feed valves used with this class of generator, it has been the common practice to provide a means whereby, as the valve is gradually opened, a cut-off plate is caused to travel across the mouth of the carbid magazine, forming a positive cut-off as the valve is opened. In this, the usual manner of construction, it is customary to place the cut-off plate slightly above the bottom of the carbid feed shoe, which construction is very inefficient inasmuch as the carbid will frequently become clogged between the plate and the walls of the feed shoe, whereby the valve will be caused to become defective and inoperative. It is especially to avoid these objectionable features that I have constructed my improved form of carbid feed valve which is so constructed that carbid will normally be discharged from the aperture formed in the walls of the feed receptacle or shoe upon a slight tilting movement of the receptacle comprising the valve.

Should a heavier pressure be desired upon further lowering movement of the gas bell the valve will be tilted farther, thereupon bringing the aperture in the wall of the carbid receptacle comprising the valve into direct registry with the mouth of the carbid magazine, permitting a direct discharge

of the carbid therethrough. If for any reason the mechanism should become defective, or from any unforeseen cause the valve should be caused to open dangerously so that 5 a dangerous pressure should be caused to form within the casing, my improved form of valve will swing across the mouth of the carbid magazine and the aperture will be closed by an emergency cut-off plate disposed 10 on the opposite side of the mouth of the magazine, as will be hereinafter described. Hence it will be seen that this valve provides a means for normal discharge of the carbid and provides also for 15 direct discharge of the carbid and lastly provides for emergency cut-off when the valve is swung to a dangerously wide open position. These features are not attainable by the use of any of the valves constructed 20 in the generators of the present day type and the further novel features of my valve will be brought out in the description.

Referring more particularly to the drawings in detail in which like reference numbers indicate like parts I have shown and described my invention as applied to a generator of the pit type having a substantially cylindrical casing provided with a frusto-conical base portion and having at its top 30 a substantially conical shaped lid or cover to be removably secured thereon and provided with an opening in its top to provide a breathing port for the machine, all of which, cover, casing and frusto-conical 35 bottom portion, are generally designated as at A. Suitable pipes are provided on the walls of the casing and so connected to the interior as to provide an efficient service main and the manner of construction and 40 arrangement of these pipes forms no part of my present invention but has been described and claimed by me in a copending application filed with the present one. The generator is provided in its interior, with 45 an inner shell 1 between which shell and wall of the generator casing operates a gasometer 2 within a water seal provided at the bottom portion of the inner shell. As a means for regulating the amount of water 50 used in the formation of this water seal I provide a vent 3 formed through the wall of the inner shell at a point which is desired to control the level of the water within the water seal. The gas bell is formed with a 55 securely attached cover thereon, as at 4, which cover is provided with handle members for lifting same out of the generator casing; and the gas bell is also provided with a suitable cap 5 centrally located in 60 the cover and adapted to provide a means whereby access may be had to the interior of the generator through the cover of the gas bell or gasometer. This cap or cover is fastened in any suitable manner and is provided 65 with a vent valve of the usual type

and provided with a curved handle 6, which owing to its curved construction provides a positive means of limiting the actuation of the vent valve to avoid any possibility of the valve being opened too wide or of being 70 turned past its closed position when it is desired to shut off the valve.

All parts of the generating chamber are disposed beneath and within this movable gas bell or gasometer and comprise in detail 75 a carbid magazine 7 having a downwardly inclined and contracted mouth 8 and being removably positioned on the inner shell 1 by means of supporting lugs suitably secured to the inner shell at desired points on the interior of the shell. At one side of the frusto-conical bottom portion of the generator which is adapted to contain the water therein is an upwardly extending sludge removing pipe 9 which is suitably supported with 80 in the casing and is extended upwardly adjacent the wall of the inner shell which is provided with a suitable bearing for the pipe at its top as at 10, the upper end of pipe 9 terminating slightly above the top of the inner shell. To accommodate this pipe and to accommodate the valve operating rod to be hereinafter described, I provide a substantially segmental open portion 11 in the wall of the carbid magazine which has an 85 open bottom portion and a removable inclined top as at 12. The closed top 12 of this segmental open portion 11 is provided with a suitable bearing which is apertured to receive therethrough a vertically extending 90 valve operating rod 13 normally projecting above the top of the carbid magazine to be forced downwardly under action of the gas bell on the operation of the valve. When in position, the closed upper portion 105 12 is disposed over the upper end of the pipe 9 to provide a closure or cover therefor; and extending over this closed portion and over the entire upper end of the magazine is a removable cover 14 provided with suitable 110 means whereby it may be removed from the magazine, and it is also provided with an aperture to receive therethrough the upwardly extending portion of the valve operating rod. 115

On the downwardly inclined bottom of the carbid magazine is attached an annular water shed member 15 to prevent any water of condensation from coming in contact with the carbid contained in the valve of the 120 mechanism.

Pivottally mounted on the mouth of the carbid magazine by means of arms 16 is a weighted carbid shoe or receptacle 17 disposed so as to swing below the mouth of the 125 magazine. This shoe or receptacle as it will be hereinafter described is formed with a closed bottom and provided with an aperture as at 18 in one wall. The receptacle is pivoted so as to oscillate below and across 130

the mouth of the magazine and is so formed as to receive a lower projecting portion 19 of the mouth of the magazine within the receptacle, and extends slightly above the closed bottom portion of the receptacle, whereby to normally dispose a small amount of carbid within the receptacle. The aperture 18, which is adapted to act as a discharge aperture for carbid from the receptacle, is disposed at one side of the mouth of the magazine, whereby, when the receptacle is in normal inoperative position, carbid will be held therein for discharging through said aperture when the receptacle is tilted or oscillated across the mouth of the hopper as hereinafter described. At the opposite side of the mouth of the magazine and supported by arms 20, rigidly secured to the magazine and depending therebelow, is an arcuately formed cut-off plate 21 disposed below the path of swinging movement of the receptacle, so as to effectually close the discharge aperture 18 when the latter is swung over the cut-off plate by the downward movement of the valve operating rod 13.

In Fig. 1, I have clearly illustrated the specific construction of my improved carbid receptacle which is disposed below the mouth of the magazine and I have illustrated the means for providing automatic cleaning of the valve comprising a raised portion 22 surrounding the mouth of the aperture 18 and projecting outwardly from the receptacle whereby to sweep over the plate 21 when the aperture is alined therewith and to prevent the lodging of any carbid thereon in a manner to obstruct the movement and hinder the operation of the valve or receptacle.

In the operation of my improved feed valve the operating rod 13, which is suitably bent to provide a water shed thereon, is forced downwardly as the gasometer is lowered, whereby the feed receptacle 17 will be slightly tilted thereby allowing a small portion of the carbid collected in the receptacle to roll through the aperture and generate a sufficient amount of gas within the chamber to raise the gasometer from contact with the operating rod, and this enables the weighted portion of the receptacle to return the receptacle to its normal position, thereby disposing the closed bottom portion of the receptacle slightly below the downwardly projecting mouth portion 19 of the carbid magazine. If for any reason the lumps of carbid should become so arranged as to retard the flow from the magazine the pressure of the gas within the chamber will be decreased and the gasometer will be lowered so as to cause the tilting of the receptacle 17 to bring the aperture 18 in registry with or directly below the mouth of the magazine, whereby a direct discharge of carbid from

the magazine will be permitted therethrough which will ordinarily be sufficient to allow sufficient pressure generated to again raise the gasometer and restore the parts to normal working position. If for any unforeseen reason the parts of the mechanism should become defective or deranged in such manner as to cause the rapid lowering of the gasometer, the receptacle comprising the valve would be swung clear across the mouth of the magazine so as to bring the aperture 18 into alinement with the upper face of the arcuate cut-off plate 21, thereby providing a positive emergency cut-off for the valve in its opened position to absolutely prevent any dangerous run of carbid from the magazine. The raised portion 22, surrounding the discharge aperture 18, will sweep across the plate 21 and dislodge any lumps of carbid which may have collected thereon so as to prevent their hindering the operation of the valve thereby providing automatic cleansing means for the valve.

In the normal operation of the generator, the gasometer will rise and fall only slightly between charges, thereby providing a slight tilting of the carbid feed receptacle which is sufficient to cause a small discharge of carbid through the discharge aperture therein without bringing the same into direct alinement with the mouth of the magazine. This gradual rise and fall thus obtained will insure a uniform pressure within the generator which is very desirable and which will be maintained owing to the free flow allowed the carbid within the receptacle and through the discharge aperture thereof, as it will be seen that there are no baffles or members formed within the receptacle itself to check or obstruct in any manner the flow of the carbid therein. The walls of the receptacle are so formed as to provide directing faces for the carbid, the wall of the receptacle having the discharge aperture therein being of a sufficient height to provide a retainer for the carbid thereon when the valve is opened to its widest position with the discharge aperture closed by the emergency cut-off plate 21, whereby the carbid will be prevented from dropping over the sides of the receptacle and thus destroying the utility of the cut-off plate.

The arms 16 are so united with the weighted end of the receptacle 17 as to allow the disposal of supporting arms 20 of the emergency cut-off plate 21 between the arms 16 and the adjacent side of the receptacle 17, and thereby to provide a positive guide for the swing of the receptacle. The arms 16 are pivotally connected on the magazine so as to provide for concentric arrangement of the line of travel of the feed receptacle 17 within the line of the arcuate formation of the cut-off plate 21. These minor details however, I do not specifically

rely upon as it is obvious that changes may be made in these details of construction without in any way departing from the spirit of my invention and the principle thereof. Located in the generating chamber and at one side of the magazine is a filter (not shown) having connection with the surface main, the filter as well as the arrangement, construction and disposition of the other parts of the generator which I have shown but not described are parts of copending applications filed with the present one and form no specific part of my invention as described herein.

10 As a means of supporting the greater part of the weight of the carbid in the magazine I provide a conical member 19' suitably secured above the mouth of the magazine as clearly illustrated in the accompanying drawings. This member 19 relieves the valve 17 of excessive weight and prevents the carbid from "bridging" or arching over the outlet 18.

While I have shown and described certain specific details of construction and manners of operation of the component parts of this preferred embodiment of my invention I desire to be understood that I do not limit myself specifically to the details as shown and described herein but that any changes may be made in the details of construction of the parts of my invention as may fall within the scope of the appended claims.

I claim:

35 1. In an acetylene generator, the combination with the magazine, of a carbid feed receptacle having a closed bottom portion and pivoted to swing below the mouth of the magazine and provided with a discharge 40 aperture in one wall thereof, operating means to move said receptacle in one direction and thus discharge the carbid through said aperture and a plate supported in a fixed position below said receptacle and 45 adapted to close said aperture when the re-

ceptacle has moved a predetermined distance in said direction.

2. In an acetylene generator, the combination with the magazine, of a carbid feed receptacle having a closed bottom spaced below the mouth of the magazine and provided with a discharge aperture in one wall thereof and at one side of the magazine mouth, said receptacle being pivoted to swing below said mouth, operating means to oscillate said receptacle and thus discharge the carbid through said aperture, and a member disposed at the opposite side of the magazine mouth to close said aperture upon extreme tilting of the receptacle.

3. In an acetylene generator, the combination with a magazine having a downwardly inclined contracted mouth, of a carbid feed receptacle having a closed bottom and pivoted on said magazine to swing below the mouth, the mouth of said magazine extending into and spaced above the bottom of said receptacle, one wall of the receptacle having a discharge aperture therein at one side of the magazine mouth, a cut-off plate supported below said magazine at the opposite side of the mouth, an automatically controlled operating means to oscillate said receptacle to discharge carbid therefrom through said aperture at one stage and to 70 register said aperture and mouth for direct discharge of carbid therefrom at another stage and to engage said aperture over said plate to close the aperture at the extreme limit of swing of the receptacle and 75 thus cut off flow of the carbid.

In testimony whereof I have hereunto set my hand in the presence of two subscribing witnesses.

FLOYD A. RUCKMAN.
